UNITED STATES PATENT OFFICE

2,565,448

PAIL HOLDER

Clifford E. Brownell, Buffalo, N. Y., assignor to
Lisk-Savory Corporation, Buffalo, N. Y.

Application May 29, 1948, Serial No. 30,099

2 Claims. (Cl. 224—45)

1

This invention relates to a device for carrying pails or like receptacles.

In scrubbing and cleaning floors, walls, and so forth, and in other cleaning, scrubbing and analogous activities, it is frequently desirable to use two or more pails or similar receptacles. In some instances one pail may contain soapy water and another pail clear rinse water. Obviously, this is merely an example and the receptacles may contain a wide variety of detergents or solvents or other cleaning fluids or other materials.

To facilitate this type of work, there is presently available a unitary rigid device which comprises essentially a pair of pails permanently fastened to each other by being welded to a common bracket or otherwise permanently fixed in side by side relation, the bracket or the general assembly being provided with some kind of carrying means. While this device has certain advantages over the handling of separate pails, it also has attendant disadvantages. For one thing, the contents of both pails must be spilled or dumped to empty either of them. Further, the fixed joinder of the pails makes it necessary to use the device in its entirety at all times, whether two pails are needed for a particular operation or not, and, of course, a leak or other damage to one pail ends the useful life of the entire device.

The device of the present invention comprises a carrying element with which a pair of pails may be associated for joint carrying. According to the present invention, the pails are placed in secure carrying relation with respect to the holder by an extremely simple manipulation, and the arrangement is such that, without the employment of any movable parts, the pails are in such relation with respect to the holder or carrier that their own weight automatically secures them against accidental release therefrom during use of the holder or carrier. The center of gravity of a pail relative to the pail holding parts is such that the weight of a pail urges it into more intimate holding engagement with the holding parts.

In an alternative form of the invention the carrier or holder forms a unitary part of one pail with means for readily attaching another pail thereto in the same fundamental manner as in the case of the holder which detachably receives two pails. In this form of the invention the pails may also be used separately if desired, and the dumping of their contents individually is provided for.

While several specific embodiments of the present invention are illustrated in the accompanying drawings and described in detail in the follow-

2

ing specification, it is to be understood that those forms are set forth by way of example only and that the principles of the present invention are limited only as defined in the appended claims.

In the drawings:

Fig. 1 is an elevational view of one form of the holder and carrier of the present invention shown in engagement with a pair of pails;

Fig. 2 is a top plan view thereof;

Fig. 3 is an elevational view at right angles to Fig. 1 with portions of one of the pails broken away for added clearness;

Fig. 4 is a fragmentary cross-sectional view on the line 4—4 of Fig. 1;

Fig. 5 is a view similar to Fig. 3 showing another embodiment of the holder and carrier of the present invention;

Fig. 6 is a view similar to Fig. 1 showing a still further embodiment of the invention, with portions broken away;

Fig. 7 is a fragmentary cross-sectional view on the line 7—7 of Fig. 6; and

Fig. 8 is a fragmentary cross-sectional view on the line 8—8 of Fig. 6.

Like characters of reference denote like parts throughout the several figures of the drawings and, referring to Figs. 1, 2 and 3, the numeral 10 designates generally a U-shaped stamping having a flat bottom portion 11 and side wall portions 12 and 13. In this form of the invention a carrying handle 14 is connected at its opposite ends to the upper ends of wall portions 12 and 13 as at 15 and 16, respectively.

As appears best in Figs. 3 and 4, wall portion 12 is formed at its opposite sides near the top of the device with inturned flanges which form downwardly extending ears 18. Wall portion 13 is similarly formed with a pair of downwardly directed ears 19.

To assemble pail 20 with the holding and carrying device it is merely necessary to tip it very slightly and insert its rim under a pair of ears 18 and 19 at one side of the holder, then move

the pail to a vertical position where its bottom edge rests upon bottom portion 11 of the holder as shown in Figs. 1 and 2. The center of gravity of the pail 20 and its contents is such as to urge the bottom of the pail toward the holder and into firmer seating engagement on bottom portion 11. Pail 21 is associated with the holder at its opposite side in a similar manner.

It will be noted that the edges of wall portions 12 and 13 converge upwardly to complement the taper of the side walls of pails 20 and 21. Wall

portions 12 and 13 may be reinforced by means of beads 23 as shown in Figs. 1 and 3.

In the modified form of the present invention illustrated in Fig. 5 the essential construction and mode of operation is the same as previously described but the stamping is so formed as to comprise a complete, unitary and rigid holder, including the handle portion. In this embodiment the medial portion of the stamping blank has its side edges curved upwardly to form a comfortable and convenient handle 25.

From opposite sides of handle 26 the stamping extends downwardly to form side walls 27 and 28 and the ends of the stamping are bent toward each other to form a continuous bottom. The lower end of side wall 28 forms a bottom 29 and the lower end of side wall 27 provides a flange 30 which overlaps bottom 29 and may be rigidly secured thereto as by spotwelding or the like.

Ears 31 and 32 in Fig. 5 are identical with those previously described and the manner in which the holder and carrier of this embodiment is used is identical with that previously described and one of the supported pails is designated 33 in Fig. 5.

In the further modified form of the present invention illustrated in Figs. 6, 7 and 8 the holder, designated generally 34, is permanently associated with one pail, designated 35, and is detachably associated with another pail, designated 36. To this end a pair of spaced side walls 37 and 38 are provided with outwardly extending arcuate flanges 39 and 40, see Fig. 8, for spotwelding or other permanent securement to the outside wall of pail 35 as indicated at 41 in Fig. 6.

As in the embodiment of Fig. 5, side walls 37 and 38 extend downwardly from an integral handle formation 42 and side wall 37 is bent inwardly to form a bottom wall 43, side wall 38 being provided with an overlapping securing flange 44 which may be spotwelded to bottom wall 43 as indicated at 45 in Fig. 7.

In this embodiment each side wall is provided with a single downwardly extending ear 46 for engagement over the rim of pail 36. A further variation in this form of the present invention appears in Fig. 6 where the edge of bottom 44 is upturned as at 48 to engage under the bottom rim of pail 36. While not essential, this upturned flange may be incorporated in the previously described holders if desired.

The holders of the present invention may be

used in multiples to carry more than two pails. This use is of particular advantage in farming and the like where a number of buckets of feed may be carried. One convenient arrangement 5 comprises a lineal row of four pails with three holders, one between each adjacent pair of pails, the middle holder being used for the actual carrying.

What is claimed is:

10. Means for carrying a pair of pails comprising a pair of spaced generally parallel side wall portions and a flat connecting base portion integral therewith, each wall portion having outward and downward extensions at opposite sides 15 thereof adjacent its upper portion, whereby a pail may be quickly and detachably associated with each side of said carrying means by inserting the upper rim of the pail behind the downward extensions at one side of the two wall portions and then moving the bottom of the pail toward the wall portions to seat a portion thereof on the flat base portion, and a carrying handle associated with said wall portions adjacent their upper ends.
25. Means for carrying a pair of pails comprising a pair of spaced generally parallel side wall portions and a flat connecting base portion integral therewith, each wall portion having outward and downward extensions at opposite sides 30 thereof adjacent its upper portion, whereby a pail may be quickly and detachably associated with each side of said carrying means by inserting the upper rim of the pail behind the downward extensions at one side of the two wall portions and then moving the bottom of the pail toward the wall portions to seat a portion thereof on the flat base portion, the edges of said side wall portions being slanted to approximately complement the taper of the sides of the pails, 35 and a carrying handle associated with said wall portions adjacent their upper ends.
40. CLIFFORD E. BROWNELL.
